BRASSIERE

Charles Rosenbaum, New York, N. Y.

Substituted for abandoned application Serial No. 61,760, November 24, 1948. This application November 23, 1954, Serial No. 470,650

4 Claims. (Cl. 2—42)

This invention relates to new and useful improvements in brassieres, and, more particularly, the aim is to provide a novel and valuable brassiere of relatively simple construction yet a brassiere with the parts thereof so arranged and coacting while the brassiere is being worn that the cups thereof enclose and maintain separated and properly uplift the breasts while holding them forwardly projected, in an improved manner. This is a substitute for my former application filed on November 24, 1948, Serial Number 61,760.

A feature of the invention is the provision of a breast cup having an ideally modified yet generally conical form, and this preferably as the result of the employment of a single blank cut in such wise and so stitched along meeting edge portions of the said blank to provide a single seam rising along the height of the cup to and somewhat beyond the apex of such cone.

A further feature of the invention is the provision of a breast cup, preferably made as just described, which is maintained in its generally conical form, and particularly against localized outward bulgings consequent upon stretch of the material of the cup, to an extent to keep the cup from departing from the norm of said conical form, by the addition of a plurality of spaced substantially concentric and generally circularly extending non-stretchable tapes stitched to the cup preferably at the interior thereof.

In combination with the two breast cup structures, a chest encircling main member or structure is provided for carrying the two breast cups at correctly horizontally spaced locations, as is conventional, but said strap member or structure according to the present invention is of improved construction and of a construction especially adapted to coact with the revised functioning of the breast cups.

A feature of the invention, in the last connection, is the making of said main member or structure, which may be called the chest girdle, of two reversely arranged like pieces of a substantially non-stretchable textile material each having a reduced forward end extension attached to the outer side and along the bottom of the base of the adjacent breast cup, a third piece of substantially non-stretchable textile material having the outline of an inverted V and attached at its opposite sides along the remainder of the bottoms and along the inner sides of the bases of both breast cups, and a piece of elastic webbing of the outline substantially of an upright triangle which preferably is an isosceles triangle and attached along its upwardly converging sides to the inner of the two legs of said inverted V.

Thereby, for coaction with the behavior of the brassiere while under horizontal-stretch stress across the front of said girdle and between points on the latter below the apices of the two breast cups, four rather closely adjacent seams are present, these variously inclined from the vertical, for conjointly functioning as parts of a set of stay-means to hold the central front portion of said girdle

2

flat against the inter-breasts space of the body of the wearer.

Various other features and advantages of the invention will become apparent or be pointed out hereinafter.

5 For further comprehension of the invention, and of the objects and advantages thereof, reference will be had to the following description and accompanying drawing, and to the appended claims in which the various novel features of the invention are more particularly set forth.

10 In the accompanying drawing forming a material part of this disclosure:

Fig. 1 is a front elevational view showing a now favored embodiment of the invention, with said girdle spread substantially flat.

Fig. 2 is an end elevation, looking toward the left in Fig. 1.

Fig. 3 shows the components of a breast cup structure, fabricated by stitching together certain like edge portions of a blank component thereof, prior to inclusion of two such breast cup structures in the brassiere in relation to the remainder of the garment as illustrated in Fig. 1.

15 Referring to the drawing more in detail, the brassiere of Figs. 1 and 2 is shown as comprised of the already mentioned chest girdle, this as a whole designated 10, a pair of breast cups 11, and a pair of conventional shoulder straps 12, each of these last shown as including two strap elements connected by a friction-type buckle 14 whereby these shoulder straps are adjustable as to length.

20 For varying the unstretched body girdling length of the chest girdle 10, the same is shown as provided at one end, at the location of a suitable inside finishing off and reinforcing strip 15, with a plurality of the hook elements 16 of the familiar hook-and-eye class of fastener.

25 For selective use in coupling relation to said hooks, the other end of the chest girdle 10 is shown as provided with two blanks 17 and 18 of the eye elements complementary to the said hooks 16. The elements 17 and 18 are secured on an end-piece 19 formed of a suitable plurality of stepped plies of a non-stretchable textile material. Said end-piece 19 is stitched at its inner end to one end of an elastic webbing strip 20 with its stretch in the direction of length of the chest girdle; and said strip 20 is stitched at its inner end to the adjacent end of the chest girdle.

30 35 40 45 50 55 60 Each breast cup 11 is made from a single blank 21 of a non-stretchable textile material. Such blank 21, as will be noted from Fig. 3, is largely bounded by a generally convexly curvilinear edge extending from a point 22 to a point 23, with, preferably, said edge including a straight edge portion 24 beyond the point 22, next a straight edge portion 25 extending at an obtuse angle from the straight edge portion 24, next a straight edge portion 26 extending at an obtuse angle to the straight edge portion 25, and next a rather long arcuately curved edge portion 27 connecting the edge portion 26 and the point 23. The center of the circle containing such arc is substantially at the point 28. The remainder of the perimeter of the blank 21 is comprised of substantially straight edge portions 29 and 30 merging into small-radius convexly curved ends 29a and 30a leading to the point 28.

65 Before being formed into a breast cup 11, a blank 21 has attached thereto, as by suitable lines of stitching as indicated, a plurality, here shown as three, of non-stretchable tapes 31, 32 and 33. These tapes are arcuately extended along circles of differing diameters but all concentric with the point 28.

70 The blank 21 as thus equipped with said tapes 31—33 is formed into a breast cup 11 by stitching together the edges 29 and 30, from the points 22—23 to the point 28, to establish a seam and to secure at said seam the oppo-

site ends of the tapes 31—33; such seam to be at the inside of the garment.

At 34 in Fig. 2 is indicated a soft, preferably netted and gauze-like fabric liner for each breast cup. This liner is for giving a breast cup an interior finish and to provide a protective and irritation-inhibiting overlay relative to the tapes and seam last-named; such a seam being designated 35 in Figs. 1 and 2. The liner 34 is cut to the same shape as the blank 21, and the edges of the liner corresponding to the edges 29 and 30 of said blank are secured together at the seam 35 of its breast cup 11.

The chest girdle 10 includes two like pieces 36, 36 of non-stretchable textile material cut to have finally the outline illustrated in Fig. 1; these pieces being reversely arranged for symmetrical placement thereof in the chest girdle as shown; and said chest girdle further includes a central piece 37 of non-stretchable textile material, this piece 37 being substantially of inverted-V outline. With each piece 36 at its inner end seamed as shown to the adjacent end of the central piece 37, and with short non-stretchable tapes 38 secured along the two seams last referred to, stay elements are established at said seams which are inclined from the vertical and downwardly converge.

The two breast cups 11 made as above described are arranged on the structure 37—36—37 with the seams 35 of said cups positionally related as illustrated, and then each breast cup is secured to the piece 37 and to one of the pieces 36 by an arcuately extending seam 39, which seam extends from its terminus 39^a (corresponding to about the point marked 39^a in Fig. 3) to its other terminus 39^b (corresponding to about the point marked 39^b in Fig. 3). Thus the major portion of the basal perimeter of a breast cup 11 is attached, in larger part, to a piece 36 of the chest girdle 10, and, in lesser part, to the piece 37 of said girdle.

The chest girdle 10 is suitably finished off, preferably at the interior of the garment, as by the addition of marginally applied tapes inclusive of two bottom tapes 40, 40, and a top tape 41. Each bottom tape 40 is shown as extended from the outer end of a piece 36 of the girdle 10 to and across a tape 38 and to the inner extremity of one of the two downwardly diverging legs of the central piece 37 of the girdle. The top tape 41 is shown as extending over the entirety of the undulatory upper length of the girdle, from the reinforcing strip 15 to the end of the girdle main structure where the same is stitched to the elastic webbing strip 20.

Along the central M-extended portion of the length of said tape 41, the remainder of the basal perimeters of the two breast cups 11 are secured to the chest girdle 10, thereby imparting to said cups their inverted-V top portions as illustrated in Fig. 1. At the crests of these last-named top portions, the strap elements of the shoulder straps 12 which carry the buckles 14 are at their lower ends secured to the chest girdle. In accordance with good manufacturing practice, the marginal portions of the chest girdle 10, all around the latter, and the marginal portions of the cups 11, all around their basal ends, may be inturned for finishing off purposes.

Consistent with its outline generally suggestive of an inverted V, the central piece 37 of the chest girdle 10 has a bottom cut-out of inverted-V type. Set in this cut-out is an insert 42 of elastic webbing. Said insert is as shown preferably in the shape of an isosceles triangle, and is cut to have its direction of stretch parallel with the base of the triangle. The insert 42 along its two sides rising from said base is secured to the piece 37 at the cut-out of the latter by lines of stitching which attach a single non-stretchable tape 43. It is to be noted that each of the tapes 38, and the adjacent leg of the tape 43, converge downwardly.

The breast cups 11 are properly conical, yet with rounded tips, and are held thus by the tapes 31—33. The chest girdle 10, aside from such stretch longitudinally

thereof as is permitted at the elastic webbing 20, has a special horizontal stretch at the elastic webbing insert 42, but, nevertheless, since at the inter-breasts region of the chest girdle, all over such region except at said insert 42, stretch is prevented, and particularly along the lines of extension of the two tapes 38 and of the two legs of the tape 43, the chest girdle is forced to lie flat against the body of the wearer and substantially in the plane including the root areas of the breasts. At the same time, each 10 breast is held separated, properly uplifted and comfortably seated in a breast cup having the shape characteristics just above again mentioned. This shape of a breast cup is maintained by the tapes 31—33, which prevent stretching. At the top of a cup 11 the same merges into 15 a shaped subdivision suggestive of a segment of a pyramid, which portion of the cup is subjected first to upward pull from the shoulder straps 12.

While I have illustrated and described the preferred embodiment of my invention, it is to be understood that 20 I do not limit myself to the precise construction herein disclosed and the right is reserved to all changes and modifications coming within the scope of the invention as defined in the appended claims.

Having thus described my invention, what I claim as 25 new, and desire to secure by United States Letters Patent is:

1. A blank for forming the breast cup of a brassiere, comprising a single piece of non-stretchable material shaped to have the outline of a segment greater than a 30 half segment of a substantially circular figure, the edge portions of said blank which extend toward the center of such circle being substantially straight along the major portions of their lengths, and their inner extremities being convexly curved thereby to give a rounded tip to the 35 cup consequent upon the establishment of the seam.

2. A blank for forming the breast cup of a brassiere, comprising a single piece of non-stretchable material shaped to have the outline of a segment greater than a half segment of a substantially circular figure, the edge 40 portions of said blank which extend toward the center of such circle being substantially straight along the major portions of their lengths, and their inner extremities being convexly curved thereby to give a rounded tip to the cup consequent upon the establishment of the seam, the 45 perimeter of said blank, between the outer ends of said straight edge portions, being substantially arcuately curved over about half said perimeter, and the remainder of said perimeter being made of a plurality of substantially straight lines each at an obtuse angle to an adjoining one.

3. A brassiere comprising a chest girdle carrying a pair of spaced substantially conically shaped breast cups of relatively non-stretchable material, and a plurality of reinforcing tapes stitched all along their lengths within each 50 of said cups and completely encircling the same, each of said tapes within each of said cups being wholly spaced from another and said tapes being concentrically arranged relative to substantially the top center of the respective breast cup, each of said cups having a rounded 55 tip and having a basal perimeter which is arcuately curved over about half said perimeter, the remainder of said perimeter having a plurality of substantially straight lines each at an obtuse angle to an adjoining one, said girdle having a top edge the central portion of which is of M-extension thereby to present two triangular upwardly projecting areas, said areas spaced longitudinally of the girdle, each of said cups over a part of its basal perimeter being attached to the two upwardly converging sides of one of said triangular areas, one of said substantially 60 straight line subdivisions of the basal perimeter of each cup being of a length substantially equal to the length of each of the upwardly converging sides of the respective 65 triangular areas.

4. A brassiere comprising a chest girdle carrying a 70 pair of spaced substantially conically shaped breast cups

of relatively non-stretchable material, and a plurality of reinforcing tapes stitched all along their lengths within each of said cups and completely encircling the same, each of said tapes within each of said cups being wholly spaced from another and said tapes being concentrically arranged relative to substantially the top center of the respective breast cup, each of said cups having a rounded tip and having a basal perimeter which is arcuately curved over about half said perimeter, the remainder of said perimeter having a plurality of substantially straight lines each at an obtuse angle to an adjoining one, said girdle having a top edge the central portion of which is of M-extension thereby to present two triangular upwardly projecting areas, said areas spaced longitudinally of the girdle, each of said cups over a part of its basal perimeter being attached to the two upwardly converging sides of one of said triangular areas, one of said substantially straight line subdivisions of the basal perimeter of each cup being of a length substantially equal to the length of each of the upwardly converging sides of the respective

triangular areas, another of said substantially straight line subdivisions of said basal perimeter being so shaped and arranged that, with the said first one of said subdivisions attached to one of said sides of the respective triangular areas and with the said other subdivision attached to the other of the sides of the respective triangular area, the portion of the cup extending from its apex toward the respective areas is shaped like a segment of a pyramid.
